INVENTOR

UNITED STATES PATENT OFFICE.

GEORGE H. NEVERGOLD, OF JEANNETTE, PENNSYLVANIA, ASSIGNOR OF
ONE-HALF TO JOHN A. KELLY, OF PITTSBURG, PENNSYLVANIA.

MANUFACTURE OF CYLINDERS FOR WINDOW-GLASS AND OTHER LIKE ARTICLES.

No. 829,991.

Specification of Letters Patent.

Patented Sept. 4, 1906.

Application filed June 5, 1905. Serial No. 263,864.

To all whom it may concern:

Be it known that I, GEORGE H. NEVERGOLD, a resident of Jeannette, in the county of Westmoreland and State of Pennsylvania, have invented a new and useful Improvement in the Manufacture of Cylinders for Window-Glass and other Like Articles; and I do hereby declare the following to be a full, clear, and exact description thereof.

My invention relates to the manufacture of glass cylinders such as are generally used for the making of window and other glass articles, and has special reference to the capping, handling, and cutting of said cylinders. Heretofore in the manufacture of these glass cylinders by the most approved processes, such as under what is generally known as the "Lubbers" process, it was required to handle the cylinders quickly and carefully after they were drawn from the tank, for the reason that they were liable to become severed from the cap, so that they would drop down and be destroyed before they were cut into the required lengths for forming into sheets. In such process it also required a number of men to handle such cylinders after being so drawn, so that they could be cut into the desired lengths after being placed in a horizontal position, and of course this required great care and loss of time in handling.

The object of my invention is to prevent all liability of such cylinders from becoming separated from their caps after being drawn and to provide a simple and effective means for handling and carrying said cylinders automatically, while at the same time they may be cut into lengths in such a position that a great number of men are dispensed with and all liability of the cylinders becoming destroyed by such handling and cutting is reduced to a minimum.

My invention consists, generally stated, in the novel arrangement, construction, and combination of parts, as hereinafter more specifically set forth and described, and particularly pointed out in the claims.

To enable others skilled in the art to which my invention appertains to practice, construct, and use the improvement, I will describe the same more fully, referring to the accompanying drawings, in which—

Figure 1 is a side elevation, and partly in section, of the derrick or tower for drawing

the glass cylinder, showing my invention applied thereto. Fig. 2 is a plan view of the blowpipe and showing the cap in section. Fig. 3 is a plan view of the forming-nipple. Fig. 4 is a sectional view of the lower end of the air-supply pipe.

Like symbols of reference herein indicate like parts in each of the figures of the drawings.

As illustrated in said drawings, 1 represents the usual derrick or tower for the forming or drawing of the glass rollers or cylinders 2 under this process, and at the lower end of said tower is the tank 3 for containing the molten glass 3'; from which said cylinders are drawn, while adjacent to said tank is the platform 4 for the operations in forming, handling, cutting, and performing of the duties in connection with the making of articles from such cylinders. Extending through the top 1' of said tower 1 is the air-supply pipe 5, which is adapted to move within said tower, and the air within the same is controlled by the valve 5' on said pipe and located within easy reach of the operatives on the platform 4. The end of said airpipe 5 within the tower 1 is provided with a projecting portion 6' thereon, within which is located a socket 6, and such end is connected to the arms 7' on a cross-head 7, which is adapted to slide within guides 7' on said tower, and such cross-head is operated from the bottom of the tower by means of a rope 8', connected at one end to said arms 7' and passing over a pulley or sheave 8 on the top 1' of said tower.

Extending out from one side of and from within the upper end of the tower 1 is the inclined track 9, at the inner end of which is pivoted a lever or trolley 10, having a curved inner end 10', while the outer end 10'' has a rod or rope 11 connected thereto, which extends down a sufficient distance for operating from the platform 4. A blowpipe 12 is adapted to be engaged by the trolley 10 through the medium of a pulley or trolley-wheel 13, which is mounted on one end of a forked bar 13', while the opposite end of said bar is pivoted at the upper end of said blowpipe and adjacent to a curved portion 12' on said pipe, the end of which is adapted to fit within the socket 6 on the air-pipe 5. A cup-shaped socket 14 is secured by a threaded

portion 14' to the lower end of the blowpipe 12, and within this socket or cup is the hollow bait or forming-nipple 15, which is formed of glass and is provided with the threaded neck 15' thereon for engaging with the threaded portion 14" in the cup 14.

At the outer end of the track 9 is connected one end of a rope 16, which is adapted to pass over the sheaves 16', which are mounted or hung from any suitable support, such as is shown at 16", and then said rope passes down and around a sheave 17 and thence up and around a sheave 17', hung from the support 16", while the outer end of said rope passes down from said sheave 16' to a position within easy reach of the operatives on the platform 4 and is provided with a weight 17" thereon to counterbalance the same. A cutting-post 18 is mounted on said platform and is provided with an adjustable cutting-needle 18', extending out from a threaded-sleeve collar 18" on said post and engaging with a threaded portion 19' thereon. A thumb setscrew 19 is mounted on the sleeve 18" for adjusting the needle 18' to its proper height for cutting the desired lengths or sections from the cylinders 2, and electric wires 20 are connected to this needle in the usual manner for heating the needle to cut the said cylinder into said sections.

The use and operation of the apparatus are as follows: The cross-head 7, with the air-supply pipe 5 and blowpipe 12 hanging on the supply-pipe 5 by the curved end 12' engaging with the socket 6, are all lowered down within the tower 1 and are guided in their movements in the engagement with and drawing of the glass by the said cross-head sliding within the guides 7" on said tower. During such lowering and when the lower end of the glass-forming nipple 15 on the blowpipe 12 has reached a position that it comes in contact with the molten glass 3' in the tank 3 the operator immediately pulls on the rope 8' to raise the cross-head 7, supply-pipe 5, and blowpipe 12, and at the same time the valve 5' in said supply-pipe is opened, so as to admit air therefrom into the blowpipe 12 and through the nipple 15 against the molten glass 3', which has adhered to the end of said nipple, so that as said pipe 12 is raised such air will blow out the glass adhering to and extending down from said nipple 15 to the size required in forming a cylinder 2, as shown in Fig. 1. When the cylinder 2 has been blown to the required size and length, it is separated or severed in the usual manner from its bottom and adjacent to the molten glass 3', so that the trolley 10 can be operated by its rope 11 to place its curved end 10' under the wheel 13 on the blowpipe 12 to lift said pipe and cylinder 2 to a position for the said wheel to engage with the inclined track 9, when said trolley can be released from said wheel and

such wheel 13 will travel down said track and 65 carrying with it the blowpipe 12, to which it is connected, and the cylinder 2, depending therefrom. When said wheel 13 reaches the outer end of the inclined track 9, it will pass onto and engage with the rope 16, which is connected to such end of said track and passes over the sheaves 16', as is shown in Fig. 1, so that the cylinder 2 will then be suspended from said wheel through pipe 12 to assume a vertical position for lowering for the cutting 75 operation of the same into the desired sections or lengths. After the cylinder 2 has thus assumed this vertical position it is lowered as desired by the counterbalanced rope 16 in the hands of the operator, so that at the 80 first cutting operation the electrically-connected needle 18' on the post 18 will engage the lower end of said cylinder and sever the lower part or ragged end of the same, which will drop down through an opening 4' in the 85 platform 4 into the space below or into any suitable receptacle. After this operation on the cylinder 2 is accomplished the cover or plate 4" is placed over said opening 4' and the end of said cylinder is dropped down and onto the same, if desired, so that each section or length desired can be severed from the cylinder 2 by the cutting-needle 18', as shown at 90 2 by the dotted lines in Fig. 1, and as each section 2" is so cut it is placed upon the table 21 on the platform 4 for cutting the same lengthwise and for being flattened into sheets in the usual manner. After the last section has been severed from the cylinder the wheel 13 is lifted off the rope 16 to remove the 100 pipe 12 for another operation, and then such rope is raised by its counterbalancing-weight 17" to a position shown in dotted lines in Fig. 1 for another operation, while a new nipple 15 can be placed within the cup 14 on the 105 blowpipe 12, if desired and then such pipe placed on the cross-head 7 and carried to the air-supply pipe 5 to be lowered for drawing another cylinder, as before described.

It will thus be seen that my device and 110 manner of capping, handling, and cutting of glass cylinders is cheap, simple, and effective in its construction and operation, and by its practice and use the cost of the manufacture of these cylinders is greatly cheapened, while 115 at the same time they can be more rapidly made and cut into lengths than under the ordinary approved process. It will also be seen that the cylinders can be handled easily, and in capping they will be firmly held to the 120 baits on the blowpipes until they are in position to be cut into lengths or for an indefinite length of time, and being handled by a positive form of an apparatus to a position for cutting it will be evident that they will 125 not be liable to be destroyed through the handling of the same by a number of men, as are usually employed for this purpose.

Various modifications and changes in the practice, construction, design, and operation of the apparatus may be resorted to without departing from the spirit of my invention or 5 sacrificing any of its advantages.

What I claim as my invention, and desire to secure by Letters Patent, is—

1. The method herein described of making glass cylinders, consisting in placing a bait 10 against the molten glass, then applying air through said bait and against the attached glass thereon as such bait and glass are raised in a vertical position to form a cylinder, then separating said cylinder from the molten 15 glass in such position, then moving said cylinder to another vertical position, and then cutting the same into lengths while in such latter position.

2. The method herein described of making 20 glass cylinders, consisting in placing a glass-bait against the molten glass, then supplying air through said bait and against the attached glass thereon as such bait and glass are raised in a vertical position to form the cylinder, 5 then separating said cylinder from the molten glass in such position, then moving said cylinder to another vertical position, and then cutting the same into lengths while in such latter position.

3. In an apparatus for forming glass cylinders, the combination with the bait for engaging 30 with the molten glass, of a blowpipe for carrying said bait and being adapted to form a cylinder as said pipe and bait are raised in a vertical position, means for raising said pipe and the cylinder while being formed, and means for engaging with and carrying said pipe and cylinder to another vertical position for cutting the same into 40 lengths.

4. In an apparatus for forming cylinders, the combination with the bait for engaging 45 with the molten glass, of a blowpipe for carrying said bait and being adapted to form a cylinder as said pipe and bait are raised in a vertical position, means for raising said pipe and the cylinder while being formed, a track, and means engaging with the blowpipe for moving said pipe and cylinder on said track 50 in order to permit said cylinder to assume another vertical position for cutting the same into lengths.

5. In an apparatus for forming glass cylinders, the combination with the bait for engaging 55 with the molten glass, of a blowpipe for carrying said bait and being adapted to form a cylinder as said pipe and bait are raised in a vertical position, means for raising said pipe and the cylinder while being formed, a track, a wheel on said pipe, and a lever for engaging with said wheel to lift the pipe and cylinder onto said track in order to permit said cylinder to assume another vertical position for cutting the same into lengths.

6. In an apparatus for forming glass cylinders, the combination with the bait for engaging 65 with the molten glass, of a blowpipe for carrying said bait and being adapted to form a cylinder as said pipe and bait are raised in a vertical position, means for raising said pipe and the cylinder while being formed, an inclined track, means for engaging with the blowpipe for moving said pipe and cylinder onto said track, and means for engaging with said blowpipe for receiving the 70 same and cylinder from said track in order to permit the cylinder to assume another vertical position and be lowered for being cut into lengths.

7. In an apparatus for forming glass cylinders, the combination with the bait for engaging 80 with the molten glass, of a blowpipe for carrying said bait and being adapted to form a cylinder as said pipe and bait are raised in a vertical position, means for raising said pipe and the cylinder while being formed, an inclined track, a wheel on said pipe, means for engaging with said wheel to lift the pipe and cylinder onto said track, and means engaging with said wheel for receiving 85 the pipe and cylinder from said track in order to permit the cylinder to assume another vertical position and be lowered for being cut into lengths.

8. In an apparatus for forming glass cylinders, the combination with the bait for engaging 90 with the molten glass, of a blowpipe for carrying said bait and being adapted to form a cylinder as said pipe and bait are raised in a vertical position, means for raising said pipe and the cylinder while being formed, an inclined track, a wheel on said pipe, means for engaging with said wheel to lift the pipe and cylinder onto said track, 100 sheaves above said track, and a rope passing over said sheaves and connected to said track for engaging with said wheel in order to permit the cylinder to assume another vertical position and be lowered for being cut into 105 lengths.

9. In an apparatus for forming glass cylinders, the combination with the air-supply pipe, of a blowpipe, a bait on said blowpipe for engaging with the molten glass, means 110 for raising said air-pipe and blowpipe in forming a cylinder, and a hollow projection extending out at an angle from said air-pipe for permitting the suspending of the blowpipe thereon.

10. In an apparatus for forming glass cylinders, the combination with the air-supply pipe, of a blowpipe, a bait on said blowpipe for engaging with the molten glass, means 115 for raising said air-pipe and blowpipe in forming a cylinder, a hollow projection on said air-pipe, and a socket on said projection for receiving the end of the blowpipe to suspend 120 the same therefrom.

11. In an apparatus for forming glass cylinders, the combination with the air-supply pipe, of a blowpipe connected to said air-pipe, a bait on said blowpipe for engaging with the molten glass, means for raising said air-pipe and blowpipe in a vertical position in forming a cylinder, a pivoted bar on said blowpipe, and a wheel mounted on said bar for permitting the lifting and moving of said

blowpipe and cylinder in order that the latter can assume another vertical position for lowering and cutting into lengths.

In testimony whereof I, the said GEORGE H. NEVERGOLD, have hereunto set my hand.

GEORGE H. NEVERGOLD.
